UNITED STATES PATENT OFFICE.

CARL GEORG MUNTERS, OF STOCKHOLM, SWEDEN, ASSIGNOR TO ELECTROLUX SERVEL CORPORATION, OF NEW YORK, N. Y., A CORPORATION OF DELAWARE.

REFRIGERATION.

Application filed September 14, 1928, Serial No. 306,007, and in Sweden April 6, 1926.

This application is filed to replace my co-pending application Serial No. 123,109 filed July 17, 1926, and contains and claims the subject matter of said application Serial No. 5 123,109 and is to be considered as relating back to said application and as having all the rights incident thereto.

My invention relates to refrigeration and more particularly to refrigerating apparatus 10 of the absorption type. Such refrigerating apparatus or refrigerators usually comprise a generator, a condenser, an evaporator and an absorber. These parts are arranged in a system having one or more cycles of circulation. My invention is particularly concerned 15 with the circulation of absorption liquid and has for one object, amongst others, to provide a highly effective circulation between the generator and absorber of a refrigerating system 20 by the sole application of heat. My invention involves various phases of heat exchange whereby heat is conserved and a high efficiency is obtained.

Further objects and novel features of my 25 invention will be apparent from the following description taken in connection with the accompanying drawings which illustrate more or less diagrammatically some forms of the invention.

30 In the accompanying drawings:

Fig. 1 shows my invention applied to an apparatus of the type utilizing an auxiliary gas into which the cooling agent proper diffuses and evaporates;

35 Fig. 2 shows a second embodiment of the invention applied to the same type of apparatus;

Fig. 3 shows still another embodiment applied to the same type of apparatus wherein 40 an auxiliary circulation of generator liquid is combined with the generator absorber circulating system;

Fig. 4 shows a fourth embodiment applied to the same type of apparatus with a different 45 arrangement of parts than shown in the previous figures.

Fig. 5 is a side view of an apparatus, built and operated, embodying the invention;

50 Fig. 6 is a similar view to that of Fig. 5 with parts in cross-section;

Fig. 7 is an end view of the apparatus of Fig. 5;

Fig. 8 is a side view of a modified arrangement of the apparatus of Fig. 5; and

Fig. 9 is an end view of the apparatus of 55 Fig. 8 with parts in section.

While I have described my invention as applied to a refrigerating apparatus of the type utilizing an auxiliary gas and while the novel features of my invention serve to coact 60 with that type of apparatus with high efficiency, it is to be understood that my invention is not limited to that type of apparatus.

Referring more particularly to Fig. 1, reference character 10 designates the generator 65 which contains the cooling agent, for instance ammonia, dissolved in a suitable absorption liquid such as water. Although it is obvious that various substances may be used as cooling agent, ammonia is preferred 70 but, in describing the apparatus as using ammonia and specific related substances, it is to be understood that this is by way of example only and without limitation. Ammonia vapor is expelled from the solution in the 75 generator, which solution is designated by reference character 11, and passes through conduit 12 and through a radiator 13 situated on an inclined portion of conduit 12 so arranged that water vapor which may pass 80 along with the ammonia vapor is condensed in this inclined portion of conduit 12 and returns to the generator. The ammonia vapor passes through radiator 13 and into condenser 85 14 which consists of a coil 15 surrounded by a water jacket 16 or other suitable cooling means. The ammonia is condensed in the condenser to liquid form and flows through conduit 17 into evaporator 18. Within the

90 evaporator is a series of perforated baffling members 19 which may be of various types. These baffling members serve to distribute the liquid ammonia over a large surface for the purpose of evaporation. The evaporator is also supplied with hydrogen through conduit 95 20 from the upper part of absorber 21.

In the evaporator the ammonia diffuses into the hydrogen and simultaneously evaporates. As a result of the evaporation of the ammonia, heat is abstracted from the surroundings of the evaporator whereby refrigeration is produced. The mixture of ammonia gas and hydrogen gas formed in the evaporator 100 flows downwardly within the evaporator and

through conduit 22 into the absorber where the ammonia gas is absorbed by weak absorption liquid supplied to the absorber through conduit 23. As the ammonia gas or vapor is absorbed by the absorption liquid, the hydrogen gas is more or less liberated from the ammonia. Since hydrogen is very much lighter than ammonia vapor, there is produced an automatic circulation upwardly through the absorber, through conduit 20, downwardly through the evaporator and back to the absorber through conduit 22. The absorber is also provided with baffling members 19 which serve to spread the liquid over a large surface for intimate contact with the gas. The absorber is provided with a cooling jacket 24 which is interconnected with cooling jacket 16 for condenser 14.

The apparatus thus far described is set out and claimed in application Serial No. 596,646, filed October 21, 1922 by Baltzar Carl von Platen and myself jointly. For further consideration of the parts hereinbefore described, reference may be had to said application Serial No. 596,646 and to Patent No. 1,609,334 resulting therefrom.

I shall now explain the circulation between the generator and the absorber:

From the lower part of the generator a conduit 25 extends downwardly forming a loop 26 at the bottom thereof and extending, in the form of a coil 27, through a source of heat 28. The source of heat is indicated as a steam jacket although any type of source of heat may be used. Coil 27 is situated at an appreciable distance below generator 10. From coil 27 a conduit 29 extends upwardly and is connected to a coil 30 situated within the generator and submerged in the absorption liquid therein. Fluid passes from coil 30 through a conduit 31 and into a coil 32 forming part of a heat exchanger 33. From coil 32 fluid passes through conduit 23 and into the upper part of the absorber where it flows down over the baffling members 19.

Connected to the bottom part of the absorber 21 is a conduit 34 which is connected to that portion of heat exchanger 33 which surrounds coil 32. At the opposite end of heat exchanger 33 a conduit 36 leads into the upper part of the generator which is in the form of a dome 35. Rich absorption liquid passes from the absorber through conduit 34, through heat exchanger 33, through conduit 36 and into the upper part of the generator where it flows on to baffling members 37. Rich absorption liquid flows downwardly over baffling members 37 in counter-flow to vapor passing upwardly through passages of the same and the absorption liquid thus enters the lower portion of the generator and mingles with the main body of liquid therein. In the generator are provided baffling plates 38 which cause a flow of liquid in the direction of the extenuated arrow.

The operation of the absorption liquid circulating arrangement is as follows:

The heat of source 28 causes formation of ammonia vapor in coil 27 and conduit 29 becomes filled to a greater or less extent with ammonia vapor. The purpose of loop 26 is to prevent the passage of ammonia vapor upwardly through conduit 25 and to insure that all the vapor passes through conduit 29. Conduits 25 and 29 form two legs of what might be considered as a vertically posited U-tube. Each of these legs contains a body of fluid which acts downwardly due to the natural action of gravity. Conduit 25 contains only liquid. Conduit 29 contains vapor or a mixture of vapor and liquid. The downwardly directed gravitational force in conduit 25 due to the head of liquid therein is considerably greater than the downwardly directed gravitational force in conduit 29 due to the head of vapor and liquid therein. Consequently there is a preponderance of downwardly directed force in conduit 25 which can be utilized and is utilized to move fluid downwardly in conduit 25, through coil 27 and upwardly in conduit 29. Movement of fluid is thus produced. The vapor of ammonia formed in coil 27 passes through conduit 29 and into coil 30 which is within the liquid space of generator 10. The vapor being hotter than the liquid in generator 10, there is a flow of heat from the inside of coil 30 to the body of liquid 11. This results in condensation of the vapor of ammonia within coil 30 and results in generation of vapor in generator 10 from solution 11. This is in part due to the fact that there is weak absorption liquid in coil 30 and strong absorption liquid in the generator proper. Strong or rich absorption liquid has a lower boiling point than weak absorption liquid. Liquid absorption liquid flows through conduit 31 and into coil 32. Here there is again an exchange of heat. The rich liquid which passes from the absorber through conduit 34 and into heat exchanger 33 is considerably colder than the weak absorption liquid passing into coil 32 from coil 31. As a result, heat is transferred from the weak absorption liquid in coil 32 into the rich absorption liquid outside the same. The weak absorption liquid is forced through conduit 23 by the preponderance of force previously described in the U-tube 25-29 and enters the absorber where it absorbs ammonia gas as has previously been explained. It will be noted that the height of conduits 25 and 29 should be so chosen that a sufficient preponderance of gravitational force is obtained to overcome the liquid column between the lower part of coil 30 and the upper portion of conduit 23 where the latter conduit connects to the absorber.

By means of baffling members 37 the rich absorption liquid is at high temperature when

it joins the main body 11 and the vapor produced in the generator has a lower temperature when entering conduit 12 than would otherwise be the case. This results in higher economy since less heat is required to be supplied for expulsion of vapor in the generator.

Baffling members 38 in generator 10 serve to maintain a proper difference of concentration of solution 11. It will be noted that the 10 flow of liquid, as indicated by the arrow is counter to the flow through coil 30. Conduit 25 is connected to that point of generator 10 where the absorption liquid is weakest.

It will be seen from the above description 15 that vaporization is produced in the conduit leading from the generator to the absorber.

In Fig. 2 there is a double circuit corresponding to the U-tube 25-29 of Fig. 1. Weak liquor from the generator flows downwardly through conduit 40 and passes into coil 41 which surrounds a heating unit 42. The 20 heating unit consists of a heating resistance adapted to be suitably connected to an electric circuit. Heat is transmitted to the liquid in coil 41 causing the same to vaporize and the vapors rise through conduit 43 passing into a coil 44 which is arranged within the lower part of generator 10 and which is situated in the liquid space thereof. The coil 44 corresponds to coil 30 and in this coil ammonia 25 is condensed while the coil serves as a heating unit for the generator. From coil 44 a conduit 45 leads downwardly to a second heating coil 46 which surrounds the electric heating element 42. In this coil also there is formation of vapor which passes upwardly through conduit 47 and into coil 48, which latter coil is situated in the solution 11 above coil 44. From coil 48 liquid passes into heating coil 32 situated within heat exchanger 33 and thence through conduit 23 into absorber 21 as in the previous embodiment. Rich liquor passes through conduit 34, through heat exchanger 33 and through conduit 36 into the 40 generator as in the previous modification.

The heavier column of liquid in conduit 40 with respect to the column of fluid in conduit 43 causes a force for movement of fluid. The heavier column of liquid in conduit 45 compared to the column of fluid in conduit 47 causes a second force for moving fluid. These two forces are additive. The apparatus being arranged so that the force thus obtained preponderates over that determined by the height of the upper part of conduit 23 above coil 48, a circulation of liquid and gas is obtained as indicated by the arrows.

In the arrangement shown in Fig. 3 a single coil is used in the generator. Liquid flows 45 downwardly through conduit 50 and is vaporized in coil 51 whereupon the vapor passes through conduit 52 and into coil 53. The conduit 52 is extended upwardly to a little higher than the level at which conduit 23 enters

the absorber in order to obtain stability of circulation. In addition to the circulation obtained by heating the liquid passing to the absorber, the nature of which will be readily understood from the previous description, there is included in the modification of Fig. 3 50 a circulating system comprising conduits 55, 56 and coil 57. This serves to heat the generator in addition to the heat transferred to the generator from coil 53.

With the arrangement shown in Fig. 2 it 55 will be noticed that the heating element 42 can be arranged nearer the generator than where there is only one coil in the path of liquid from the generator to the absorber. The proximity of the source of heat to the 60 generator can be determined and can be diminished by proper arrangement of conduits. By placing the absorber so that it extends horizontally rather than vertically, the conduit 23 can be made of less height and thus the 65 total height of the apparatus can be considerably diminished.

In Fig. 4 I have shown an arrangement wherein the absorber is placed horizontally. For the sake of illustration I have shown the 70 evaporator which is designated by reference character 60 as situated above the absorber but it will be understood that the evaporator can be placed opposite the absorber as shown in the previous modification whereby an apparatus can be obtained of extremely small vertical extent. In the modification shown in Fig. 4 two coils are used as in Fig. 2 but the coils are placed horizontally rather than vertically. Liquid passes downwardly from 75 the generator 10 through conduit 61 and through coil 62. Heat is transferred from the source of heat 63 to the contents of coil 62 and vapor is formed which passes upwardly through conduit 64 and into coil 65, in which 80 the vapor is recondensed. The fluid passes downwardly through conduit 66 and through coil 67 in which the fluid is again vaporized. Vapor (and possibly some liquid) passes upwardly through conduit 68 and into coil 69 85 which is situated in solution 11. From coil 69, in which recondensation again takes place, the absorption liquid passes through a coil 70 which is coiled around the generator. Coil 70 forms the inner tube of a coil heat exchanger of which the outer tube is designated 90 by reference character 71. After passing through tube 70 the absorption liquid enters a horizontal conduit 72 which extends along the upper part of the absorber 73. The weak absorption liquid issues from the open end of conduit 72 indicated by reference character 74. Rich absorption liquid passes from the absorber through conduit 75 and into tube 71. After passing through tube 71 and outside tube 70 the rich absorption liquid enters 95 the upper part of the generator through conduit 76 which corresponds to conduit 36 of

the previous modification. The rich absorption liquid passes down in the direction of the long arrow and to conduit 61. A baffling member 78 is provided in the generator to obtain efficient heat translation.

Circulation of auxiliary gas between the absorber and evaporator takes place through conduits 80, 81, 82 and 83. Conduit 81 is arranged outside a portion of conduit 83 to form a heat exchanger for transferring heat from conduit 83 to the gas mixture within conduit 81. In the arrangement shown in Fig. 4 the rectifier 85 is arranged vertically and consists of a cylindrical casing 86 enclosing a series of baffling members 87. The ammonia condenser 89 has a cooling jacket 90 which is interconnected with a cooling jacket 91 surrounding the absorber.

By using a horizontally disposed generator as herein disclosed, a large vapor disengaging surface is obtained. This tends towards high efficiency. Figs. 5, 6 and 7 show an apparatus which has been built and operated with practical refrigerating results and which embodies the principles of the invention above brought out in connection with the preceding figures. In order to indicate the relationship of this apparatus to those previously described, like reference characters will be used to designate like or corresponding parts, the reference characters of Fig. 1 being applied to Fig. 5, 6 and 7 to illustrate the relationship.

The generator 10 of Fig. 5 is placed below the absorber 21 but above heat exchanger 33. Below heat exchanger 33 is a generator 27 which corresponds in part to coil 27 of Fig. 1 and therefore is so designated. Connected to generator 27 at the right hand end, as shown, is a relatively large vertically extending conduit lettered 25 below a connection 25^a to generator 10 and which is lettered 12 above a connection 12^a to generator 10. Relatively weak absorption liquid flows from the lower part of generator 10, through connection 25^a, downwardly through conduit 25 and into generator 27. From generator 27, weak absorption liquid passes into coil 27^a. Generator 27 and coil 27^a are heated by means of a gas burner or electric heater inserted in a flue 28 around which coil 27^a is wrapped. Due to heat applied to coil 27^a, the weak absorption liquid flows upwardly through conduit 29 and thence through a coil 30 within generator 10. Coil 30 is out of communication with the space around the coil within generator 10. Vapor of the cooling agent, ammonia, is produced in generator 10 due to the heating effect of the contents of coil 30 and passes through connection 12^a into conduit 12 and thence to the rectifier and condenser. Ammonia is also expelled, as vapor, from solution, in generator 27 and passes upwardly through conduit 25 in counter-flow to the downwardly flowing absorption liquid.

From coil 30, the weak absorption liquid

passes through connection 31, through the outer conduit of heat exchanger 33 and through conduit 23 into the upper part of the horizontal absorber 21 containing horizontal trays 19.

Strong absorption liquid flows from the bottom of absorber 21 through conduit 34 and into vessel 100. A gas connection 101 connects the top of vessel 100 with the absorber. From vessel 100, the strong absorption liquid passes through conduit 34^a, through the inner conduit of heat exchanger 33 and thence through conduit 36 into generator 10.

Vapor passing upwardly through conduit 12 is rectified in rectifier 13 which receives liquid ammonia from the condenser 14 through conduit 103 and which has a vapor connection 104 with the condenser. A rectifier of this type is shown in my application Serial No. 132,160. The entrained water vapor is separated out and the ammonia vapor passes into the condenser where it is liquefied.

The liquefied ammonia passes through conduit 17 into horizontal evaporator 18 which contains horizontal trays 19 over which the liquid ammonia is distributed. Hydrogen enters the evaporator through conduit 20 and the ammonia diffuses into the hydrogen forming a gas mixture which passes out through conduit 22 and through a heat exchanger 105. The heat exchanger contains a plurality of tubes 22^a which are spread at the ends to form heads. The gas mixture passes through tubes 22^a and through conduit 22^b and thence to absorber 21.

Hydrogen leaves absorber 21 through conduit 20^a and thence through outer shell 20^b of heat exchanger 105, whence it passes through conduit 20 to the evaporator. The circulation of the gaseous fluid between and through the evaporator and absorber is maintained on account of the differences in specific weight of the fluids in different vertically extending conduits.

A cooling coil 24 surrounds absorber 21 and carries cooling water for cooling the absorber. After passing through coil 24 the cooling water passes through conduit 106 and to and through conduit 16, the cooling conduit for the condenser. A conduit 107 connects the vertical gas heat exchanger 105 with conduit 31 for venting any gas not converted to liquid in coil 30.

The apparatus shown in Figs. 8 and 9 includes a plurality of coils which are heated by the source of heat and therefore is lettered along the lines of Fig. 4 as respects the arrangement of generator and associated parts.

The weak liquor flows through connection 25^a and down through conduit 25 into the lower generator which is here designated as 62. This generator is similar to generator 27 of Fig. 5. Thence the absorption liquid flows through coil 62^a, where it is heated, and upwardly through conduit 64 and through a coil

70

125

130

65 in one of two generators 10^b and 10^c which are disposed at the same level. These generators are connected by upper and lower connections 110 and 111 respectively. After passing 5 through coil 65 the absorption liquid passes downwardly through conduit 66 and through coil 67, where it is again heated, and thence upwardly through conduit 68 and through a coil 69 within generator 10^c. After passing 10 through coil 69 the absorption liquid passes through connection 31 and into heat exchanger 33.

The absorber 21 in this case is arranged vertically which necessitates a higher lift of absorption liquid. It will be noted that the only substantial difference between the device shown in Figs. 5 to 7 and the device shown in Figs. 8 and 9 is that, in the latter instance, the absorption liquid is twice elevated by thermosiphon coils and twice condensed in the generator. The operation of the device shown in Figs. 8 and 9 will be apparent from the operations above described.

In applying the apparatus shown in Figs. 25 5 and 8 for a refrigerating cabinet, it will be readily seen that the absorber and generator are fitted below the insulated food space of the cabinet, the evaporator 18 projects into the food space of the cabinet and is suitably 30 equipped with a heat transfer member comprising ice trays, and the vertical gas heat exchanger and other vertical conduits adjacent thereto pass outside the insulated food space either at the side or the back of the cabinet.

35 While I have disclosed various forms of my invention it is to be understood that my invention is not limited to the particular embodiment set out.

Having thus described my invention, what 40 I claim is:

1. Refrigerating apparatus comprising an evaporator, an absorber, a generator, means to receive vapor from the generator, liquefy the vapor and conduct the liquid to the evaporator, a source of heat, a conduit within said generator adapted to carry fluid of different pressure than the pressure of fluid in the generator, means to conduct weak absorption liquid from said generator into heat exchange 45 relation with said source of heat and thence to said conduit, a connection between said conduit and said absorber and means for passage of liquid from said absorber to said generator.

50 2. Refrigerating apparatus comprising a horizontally disposed generator, an evaporator, means to receive vapor from the generator, liquefy the vapor and conduct the liquid to the evaporator, an absorber, a coil 55 extending through said generator constituting a conduit separated from the liquid and vapor space of the generator and adapted to carry fluid of higher pressure than that of fluid in the generator, a heating member situated below said generator, a conduit con-

necting said generator with said heating member, a conduit connecting said heating member with said coil, a conduit connecting said coil with said absorber and a conduit connecting said absorber with said generator. 70

3. That improvement in the art of refrigerating through the agency of an absorption system which consists in simultaneously and continuously withdrawing weak absorption liquid from a main body thereof, heating the withdrawn liquid to produce a flow motivating force moving the withdrawn liquid into absorptive contact with a vaporized cooling agent under influence of the flow motivating force, transferring heat from the heated withdrawn portion to said main body on its way to the said absorptive contact, conducting enriched absorption liquid back to the same said main body and transferring heat into the returning rich absorption liquid from the weak heated withdrawn liquid before the withdrawn liquid becomes enriched by said absorptive contact. 80

4. That improvement in the art of refrigerating through the agency of a generator-absorber-evaporator cycle which consists in withdrawing weak absorption liquid from the generator, vaporizing the withdrawn portion to produce a flow motivating force, moving the withdrawn liquid to the absorber under influence of the said force and transferring heat from the vaporized withdrawn liquid to the contents of the generator to vaporize liquid in the generator and condense the withdrawn liquid on its passage to the absorber while maintaining the generator and the absorber at substantially the same pressure. 90

5. That improvement in the art of refrigerating through the agency of a generator-absorber-evaporator cycle including a pressure equalizing fluid which consists in conducting rich absorption liquid from the absorber to the generator, simultaneously withdrawing weak absorption liquid from the same said generator, conducting the withdrawn liquid through a source of heat, thence conducting the withdrawn liquid through the generator at a higher pressure than that of fluid in the generator due to the passage through said source of heat, thence into heat exchange relation with the rich liquid passing from the absorber to the generator and thence 100 upwardly into the absorber. 110

6. Refrigerating apparatus comprising an evaporator, an absorber, a generator, means to receive vapor from the generator, liquefy the vapor and conduct the liquid to the evaporator, a source of heat, a plurality of conduits within said generator, conduit connections for conducting weak absorption liquid from said generator into heat exchange relation with said source of heat, thence through 120 one of said plurality of conduits, thence again 125

into heat exchange relation with said source of heat, thence through another of said plurality of conduits and finally into said absorber, and means for passage of liquid from said absorber to said generator.

7. Refrigerating apparatus comprising an evaporator, an absorber, a generator, means to receive vapor from the generator, liquefy the vapor and conduct the liquid to the evaporator, a source of heat, a heat exchanger, a plurality of conduits within said generator, conduit connections for conducting weak absorption liquid from said generator into heat exchange relation with said source of heat, thence through one of said plurality of conduits, thence again into heat exchange relation with said source of heat, thence through another of said plurality of conduits, thence through said heat exchanger and thence into the absorber and means for passage of rich absorption liquid from said absorber, through said heat exchanger and into said generator.

8. Refrigerating apparatus comprising a generator, a source of heat and connections for repeatedly and successively conducting absorption liquid into heat transfer relation with said source of heat and into heat transfer relation with said generator at successively increasing pressures relative to the pressure in the generator.

9. Refrigerating apparatus comprising, in combination, an evaporator, a generator, means to receive vapor from the generator, liquefy the vapor and conduct the liquid to the evaporator, an absorber, means to indirectly heat the generator and circulate liquid between the generator and the absorber due to change in specific gravity of absorption liquid, said generator and absorber being both disposed horizontally and near to each other to provide a small vertical travel of absorption liquid from the generator to the absorber and a large disengaging surface.

10. Refrigerating apparatus comprising a generator, an evaporator, means to receive vapor of a cooling agent from the generator, liquefy the vapor and convey the liquid to the evaporator, an absorber situated above the generator, means for circulating an auxiliary pressure equalizing agent between the evaporator and absorber, a conduit in said generator but out of communication with the liquid and gas space of the generator so as to carry fluid of higher pressure than that of the fluid in the generator, a source of heat, a conduit arranged to receive weak absorption liquid from the generator and conduct the same into heat exchange with said source and thence to the conduit within the generator, a conduit for conveying fluid from the conduit within the generator to a high point relative to the absorber and connected to the absorber to permit flow thereinto at a higher part and a conduit for flow of fluid by grav-

ity from a lower part of the absorber to the generator.

11. That improvement in refrigerating through the agency of an absorption system including a generator containing a cooling agent dissolved in absorption liquid, a condenser, an evaporator and an absorber which consists in continuously and simultaneously withdrawing weak absorption liquid from the generator, vaporizing withdrawn liquid and lifting the withdrawn liquid to a high level relative to the absorber due to the vaporization of the withdrawn liquid; heating the generator by the withdrawn liquid on its passage to the absorber, flowing liquid from the absorber to the generator by gravity, producing vapor of the cooling agent in the generator from the same body of fluid from which the weak absorption liquid is withdrawn, conducting the vapor produced in the generator to the condenser, conducting liquid cooling agent from the condenser to the evaporator and transporting cooling agent from the evaporator to the absorber.

12. That improvement in refrigerating through the agency of an absorption system including a generator containing cooling agent dissolved in absorption liquid, a condenser, an evaporator and an absorber which consists in continuously and simultaneously withdrawing weak absorption liquid from the generator, vaporizing withdrawn liquid and lifting the withdrawn liquid to a high level relative to the absorber due to the vaporization of the withdrawn liquid, heating the generator by the withdrawn liquid on its passage to the absorber, flowing liquid from the absorber to the generator by gravity, producing vapor of the cooling agent in the generator from the same body of fluid from which the weak absorption liquid is withdrawn, conducting the vapor produced in the generator to the condenser, conducting liquid cooling agent from the condenser to the evaporator and circulating an auxiliary agent between the absorber and evaporator in the presence of which the cooling agent evaporates.

13. Refrigerating apparatus comprising a horizontally disposed generator, a source of heat situated below said generator, a plurality of conduits within said generator and means for circulating absorption liquid through the generator comprising connections for successively conducting absorption liquid through the conduits within the generator and in heat exchange relation with the source of heat in a plurality of upward and downward paths to obtain a lifting force for the absorption liquid.

In testimony whereof I have affixed my signature.

CARL GEORG MUNTERS.
